UNITED STATES PATENT OFFICE.

THOMAS M. DAVIS, OF LOS ANGELES, CALIFORNIA, ASSIGNOR OF ONE-HALF TO
EDWARD W. MCKINNEY, OF LOS ANGELES, CALIFORNIA.

T-SQUARE GUIDE.

Application filed April 4, 1925. Serial No. 20,716.

To all whom it may concern:

Be it known that I, THOMAS M. DAVIS, a citizen of the United States, residing at Los Angeles, in the county of Los Angeles, State of California, have invented a new and useful T-Square Guide, of which the following is a specification.

This invention relates to a device for guiding a T-square as it is moved to and fro along the drawing board, an object being to hold the cross head of the T-square firmly against one edge of the drawing board so as to properly align the T-square with said board at all times without the necessity of the draftsman pressing the head of the T-square against the edge of the drawing board. More particularly the device is of the type that co-operates with the cross-head of the T-square.

An object of the invention is simplicity of construction and ease of attachment to the T-square and drawing board.

Another object is to provide a device of this character that will operate properly regardless of the relative lengths of the drawing board and T-square.

Further objects and advantages will appear in the subjoined detailed description.

The accompanying drawings illustrate the invention:

Fig. 1 is a plan view of a T-square guide constructed in accordance with the provisions of this invention and applied to a drawing board.

Fig. 2 is an edge view looking up toward Fig. 1.

Fig. 3 is an enlarged broken elevation, partly in section, from the line indicated by 3-3, Fig. 1.

Fig. 4 is an enlarged fragmental sectional detail on the line indicated by 4-4, Fig. 1.

The T-square indicated at *a* is provided with a shoulder *6* adapted to engage and be guided by a member *7* which is mounted substantially parallel with one edge of the drawing board, indicated at *b*. In this particular instance, the shoulder *6* is constituted by a roller mounted on a shaft *8* which is detachably secured to the T-square. The shaft *8* is screw-threaded into one leg of a U-shaped clamp *9* and the other leg of said clamp is provided with a set screw *10* adapted to be

screwed into engagement with the under-face of the cross head *c* of the T-square. The roller thus projects from the upper face of the T-square.

The member *7* is mainly of circular cross section, the end portions being flattened as indicated at *11*. The member *7* is slidably connected with one end of the drawing board and is yieldingly held toward said drawing board. The construction for effecting this is as follows: The flattened rod portions *11* are provided with longitudinally extending slots *12* through which pass arms *13* secured by screw *14* or other suitable fastening devices to opposite edges of the drawing board. The arms *13* are each provided with an annular bend *15* so that the outer end portions of the arms that extend through the member *7* lie in a plane above the level of the upper face of the drawing board, thus holding the member *7* above the head of the T-square and in alignment with the roller *6*.

The arms *13* are provided near their outer ends with shoulders *16* which, in this instance, are constituted by nut screws threaded onto the arms *13*. Interposed between the flattened ends *11* and the ends *16* are coil springs *17* which surround the arms *13*. The springs *17* yieldingly hold the member *7* in engagement with the roller *6* so as to yieldingly hold the head *c* of the T-square in contact with the adjacent edge of the drawing board.

When the draftsman is using the invention described above, he will place his hand upon the blade of the T-square and force it away from or toward him, and the roller *6* and the member *7* will guide the T-square as it moves to and fro over the drawing board. The invention operates a great deal the same as though the draftsman employed his hand upon the head of the T-square, as is customary, to press said head against the drawing board but by using this invention the pressure is uniform and the draftsman is relieved from exerting the required pressure.

If desired, for any reason, to use the T-square on the drawing board in such manner that the invention would interfere with its proper manipulation, the screw *10* will be loosened and the clamp *9* removed so that

the member 7 will no longer function to yieldingly press the head of the T-square toward the drawing board.

I claim:

1. A T-square guide comprising arms adapted to be secured to and project from a drawing board, a rod having its opposite ends slidably engaging the arms respectively, a T-square having a shoulder, and springs on the arms yieldingly holding the rod engaged with the shoulder to urge the T-square against an edge of said board.

2. A T-square guide comprising a rod, means to slidably connect the rod at its opposite ends to a drawing board substantially parallel with one edge thereof, springs operating to hold the rod toward the drawing board, and a T-square having a shoulder on the upper face of the cross-head thereof positioned to engage the inner side of the rod when the T-square is lying on the drawing board.

3. A T-square guide comprising arms

adapted to be secured to and project from a drawing board, said arms having bends 25 therein to cause the outer end portions of the arms to lie in a plane above the level of the upper face of the drawing board, a rod slidably connected with the outer end portions of the arms, a T-square having a 30 shoulder on its upper face, and means yieldingly holding the rod toward the shoulder when the T-square is lying on the drawing board.

4. A T-square guide comprising a roller, 35 means to detachably mount the roller on a T-square, a rod, means to connect the rod to a drawing board and permit movement of the rod toward and from one edge of the board, and means yieldingly holding the rod 40 in engagement with the roller to urge the T-square against an edge of said board.

Signed at Los Angeles, California this 26th day of March 1925.

THOMAS M. DAVIS.
